CLAIM

The ornamental design for a horticultural container, as
shown and described.

DESCRIPTION

FIG. 1 is an isometric view of a horticultural container
showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines and areas within them including areas
immediately adjacent to the solid line perimeter of the
bottom of the article depict portions of the horticultural
container that form no part of the claimed design.
